DESIGN FOR A COMBINED FROZEN CONFECTION, SUPPORT, AND DRIP CATCHER

Elmer C. Texter and Carl G. Shocknesse,
Detroit, Mich.

Application July 21, 1939, Serial No. 86,160

Term of patent 14 years

To all whom it may concern:

Be it known that we, Elmer C. Texter and Carl G. Shocknesse, citizens of the United States, residing at Detroit, in the county of Wayne and State of Michigan, have invented a new, original, and ornamental Design for a Combined Frozen Confection, Support, and Drip Catcher, of which the following is a specification, reference being had to the accompanying drawing, forming part thereof, wherein:

Fig. 1 is a side elevational view of a combined frozen confection, support, and drip catcher, showing our new design; and

Fig. 2 is a bottom plan view thereof.

We claim:

The ornamental design for a combined frozen confection, support, and drip catcher, substantially as shown.
